UNITED STATES PATENT OFFICE

FRED L. MACKENZIE, OF BEVERLY, MASSACHUSETTS, ASSIGNOR TO UNITED SHOE MACHINERY CORPORATION, OF PATERSON, NEW JERSEY, A CORPORATION OF NEW JERSEY

FASTENING-PULLING MACHINE

Application filed August 26, 1930. Serial No. 477,934.

This invention relates to machines for drawing fastenings from various articles, as those for pulling the temporary securing tacks from insoles of shoes. The present case constitutes a continuation of a copending application Serial No. 719,076, filed June 10, 1924, in my name, and which matured into Patent No. 1,807,853, June 2, 1931, as to all common subject-matter.

10 The invention has as an object the provision of effective means for guiding the work to be operated upon in presenting the tacks to be pulled to the tool which is to operate upon them and for preventing injury to the work 15 by such tool.

For certain classes of work, as especially in the pulling of insole tacks, it may be desirable to vary considerably the depth to which the tool acts and still to limit the extent to which said tool enters the surface of the work into which the tacks are driven. To this end and as illustrated, the invention provides in a machine of the type referred to a pulling member or tool and gage members 25 co-operating with the tool. Preferably the gage members are adjustable relatively to the tool and to each other so that one of the gage members can be positioned to act as a guide for the work and also to serve as a hold-down or abutment resisting the pulling action of the tool, and the other gage member can be positioned to limit the extent to which the work may approach the tool, thus to prevent injury to the work. As shown, the gage 30 members are located at opposite sides of the path of movement of the tool, one of them being farther removed than the other from the point of engagement of the tool with the work. Upon the gage member having the greatest projection the work may be rocked laterally to increase or diminish the bite of the tool while the other acts as a stop determining the maximum depth of engagement. Either or both of these gages 45 may be adjustable to modify their effects.

Other objects and features of the invention will be apparent from the following detailed description when taken in connection with the accompanying drawings and 50 will be pointed out in the claims.

In the drawings,

Fig. 1 is a side elevation of my improved machine particularly arranged for pulling insole tacks;

Fig. 2 is a partial vertical section through 55 the driving shaft with which is associated an electric motor;

Fig. 3 illustrates in front elevation the 60 tack-pulling tool and gage members of Fig. 1;

Fig. 4 is a side elevation of a modified construction;

Fig. 5 is a plan view, partly in section, of the machine illustrated in Fig. 4; and

Fig. 6 illustrates in front elevation the 65 tack-pulling tool and gage members of Fig. 4.

The machine illustrated in Figs. 1, 2 and 3 comprises a base portion or frame 10 in the form of a column, the upper extremity only 70 being illustrated in the drawings. Upon the base portion 10 is secured a carrier portion, consisting of an upstanding bracket 12 offset to one side of the vertical axis of the column. At the upper end of this bracket is a generally cylindrical head 14 having its axis located horizontally, and with a bore 16 extending along this axis and arranged to receive a journal bearing. Attached to the side of the head 14 over the column is a hollow frame 75 arm 18 extending slightly upward and then forward clear of the column. Within this head is mounted an operating lever or tack puller bar 20 hung near its center for oscillation upon a link 22 pivoted upon lugs 24 depending from the upper side of the interior of the arm. At its extremity outside the arm, the lever is provided with clamping means consisting of a divided socket 26 to receive the shank of a tack-pulling tool, such as tool 28 (Figs. 1 and 3). The outer end of the tool 28 is substantially rectangular in cross-section but is tapered at its end portion the upper surface of which is provided with a gouge 29 terminating in a sharp edge 80 85 90

30. Screws 31, extending horizontally through the lever, serve to draw the opposite sides of the socket 26 together to clamp the tool 28 in place.

The inner end of the arm 20 carries a 100

strap 32 surrounding an eccentric 34. As particularly illustrated in Fig. 2, the eccentric is mounted upon a tubular spindle or shaft 36 having bearings in bushings 38 situated in the bore 16 and in an alined bore 40 at the outer side of the arm 18. The eccentric is counterbalanced by a weight 42 projecting from the spindle 36 at the side opposite the major radius of the eccentric. 10 Attached to the outer face of the head 14, opposite the arm 18, is the casing of an electric motor 44. The shaft 46 of this motor is axially alined with the spindle 36, and has an end portion 48 extending into the spindle. 15 The shaft 46 is keyed to the spindle at 50, and is held against longitudinal movement in the direction of the arm by a flange 52, while a screw 54, threaded into the shaft and having a washer beneath its head abutting 20 against the outer extremity of the spindle, draws the flange into contact with the spindle, holding these elements firmly connected. The thus-furnished bearing common to the eccentric and motor shafts gives a simple and 25 compact arrangement, insuring effective coupling and perfect alinement. Lateral play of the motor armature in axial directions in centering itself in its magnetic field is permitted by longitudinal movement of the eccentric spindle 36, there being space to permit this between the adjacent ends of the bushings 38. The lever 20 is prevented from sharing in this movement by cheek pieces 56 formed upon the interior of the arm 18, and 30 between which the lever slides. The lower portion of the arm may be formed as an oil chamber, in which the eccentric dips in its rotation, the counter-balance weight 42 splashing the oil to lubricate the bearings 40 of various of the operating parts. The depth of oil in the chamber is determinable by a gage 58, while a cock 60 is provided, through which the chamber may be emptied. A flange 62 is shown about the lever 20 just 45 within the outer extremity of the arm, thus furnishing a shield tending to exclude tacks from the arm and tending to prevent the spattering of oil on the work or the flow of oil along the lever 20.

50 The forward end portion of the arm 18 is provided with an upwardly disposed machined surface 64 to which is secured by bolts 66 a frame extension 68. Adjustably secured to the forward wall of this extension 55 by a sliding screw connection 70 is an inclined arm 72 having at its lower end a gage roll 74 rotatable about a horizontal axis and with the bottom of its periphery located slightly at one side of the path of movement 60 of the tool 28 and somewhat above the lowest point in the path of movement of the tool. Joined to the arm 72 by a slot-and-screw connection 76 is a gage member 78 situated in close proximity to the opposite 65 side of the tool from the roll 74 and having

its lower extremity with which the work contacts at a somewhat greater height than the bottom of the roll.

In pulling insole tacks with the machine organized as above described, the operator may advance the work, such as a shoe 79 (Fig. 3), along the roll 74 in a nearly horizontal position, the rotation of the roll upon its arm permitting the guiding action with but little resistance to movement. The travel of the member 28 under guidance of eccentric 34 and links 22 is preferably in an elliptical path, effective operation taking place as the tool is directed downwardly and forwardly, during which time its curved edge 30 is forced into the upper surface of the insole beneath the head of the tack, and is then raised, still with a somewhat forward movement, to withdraw the tack. If the tack to be pulled is more deeply driven, so that, with the insole held horizontally in a lateral direction, the stroke of the tool would not be deep enough properly to engage the tack, the work may be tilted up at the right side, as seen in Fig. 3, upon the roll 74 as a rest toward the gage 78. This causes the tool to be more deeply projected into the work, and thus more effectively engage the tack. Destructive effect of the tool upon the insole material is prevented by contact of the work with the gage 78, this being adjusted by its connection 76 as may be necessary to limit the digging of the tool into the work. Obviously, the operator may modify this tack-engaging action to any degree, between the lightest contact of the tool with the insole, when the side of the work removed from the roll may be horizontal or even inclined downwardly, and the maximum engagement, when the insole has been raised into contact with the gage member 78.

In the machine illustrated in Figs. 4, 5 and 6, there is provided a column 80 to which is secured a head 82 having a forwardly extending frame arm 84. Within the rearward portion of the arm is located a shaft 86 similar in construction to shaft 46 but arranged to be driven by a pulley 88. The shaft 86 is provided with an eccentric 90 operatively connected to an oscillatable lever or tack puller bar 92 by means of an eccentric strap 94 on one end of the bar. The tack puller bar 92 is supported in the arm 84 by links 96 to which it is pivotally secured at 98, the links in turn being pivoted at 100 upon lugs 102 depending from the upper portion of the arm 84. The arm 84 is provided with machined bearing surfaces 104 and 106 engaging side portions of the tack puller bar 92. The bar is forced against the bearing surfaces by bearing plates 108 and 110 which engage portions of the bar upon the opposite side thereof and which are held in position respectively by bolts 112 and 114. The bearing plate 108 is provided with a flange 116

upper and lower surfaces of which slidably engage guides in the form of lugs 118 upon the arm, thereby to prevent play of the plate heightwise of the bar 92. Bearing plate 110 is provided with a similar flange 120 for engagement with lugs 122 for a similar purpose. This construction provides means for taking up the play between the tack puller bar and its bearings, thus making it possible to obtain smooth operation of the bar when in operation, thereby reducing the vibration of the machine. The forward bearing surface 104 and its corresponding bearing plate 108 are recessed, as indicated by reference characters 124 and 126, for the purpose of receiving pieces of felt 128 which are effective to lubricate the side surfaces of the bar 92, oil being supplied to the felts by an oil cup 130. Oil is supplied to the link pivots 98 and 100 by oil cups 132 and 134.

The flange 116 of bearing plate 108 substantially closes off the forward portion of the arm 84 except for an opening 136 in the flange through which the forward portion 25 of the tack puller bar extends. Near the point where the bar passes through the opening 136 the bar is curved upwardly, as indicated by reference character 138, to clear the lower portion 140 of the bearing plate 108 and is then curved downwardly, as indicated by reference character 142. This curvature of the tack puller bar 92 tends to prevent tacks from entering into the opening 136 between the bearing surface 104 and the bearing plate 35 108 through which opening the tack puller bar operates. In this connection it will be noted that the downward curvature of the bar is such that the greater portion of such opening is covered by portions of the bar 40 which extend in a direct line between the tool and the opening.

The forward end of the arm 84 is provided with a depending extension or frame 144 upon the outer surface of which are two lugs 45 146 between which are mounted two gages 148 and 150 adjustably held upon the frame by set-screws 152 which operate in slots 154 in the gages to provide for longitudinal adjustment of each of the gages independently 50 heightwise of the frame. The gage 148 is recessed, as indicated by reference character 156, to provide passage for a tack-pulling tool 158 which is located between the gages and in close proximity to the side walls thereof. The tool 158 which is similar to tool 28 (Fig. 3) is secured to the bar 92 by a split holder 160 and clamping screws 162. As shown, the gages 148 and 150 are tapered at their lower ends and terminate respectively 55 in curved work-engaging surfaces 164 and 166. As in the case of gages 72 and 78, one gage (gage 150) is normally adjusted so that its work-engaging surface 166 is raised somewhat above the similar surface 164 of the other gage 140, whereby a shoe, such as

shoe 168, may be presented to the tack-pulling tool under the guidance of gage 148 and may be tilted upwardly about the bottom of the gage 148 as an axis in order to obtain deeper operation of the tool upon the shoe, movement of the shoe being limited by the gage 150.

The operation of the construction just described is similar to that of the construction illustrated in Figs. 1 and 3 except that the work is guided by a curved surface 164 of the gage 148 instead of by a roll 74.

It is to be noted that some operators may prefer to rock the rear portion of a shoe presented to the tools in an upward direction to pull a deeply embedded tack rather than to tilt the shoe laterally. The constructions above described can be readily adapted to operate in this manner by adjusting the gages 72 and 78 or the gages 148 and 150, as the case may be, so that their work-engaging portions lie at the same level or nearly so, in which case each of the gages will act as a guide and hold-down for the work presented thereto. The gages 148 and 150 are especially well adapted to this and other adjustments in view of the fact that they are mounted for movement relatively to the frame and tool independently of each other.

Having described my invention, what I claim as new and desire to secure by Letters Patent of the United States is:—

1. In a machine of the class described, a movable fastening-pulling member, and gage members at the opposite sides of the path of the pulling member and beyond which said pulling member is movable into engagement with the work, one of said gage members being farther removed than is the other from the point of engagement of the pulling member with the work.

2. In a tack-pulling machine, an oscillatory tack-pulling tool arranged for presentation of the work in a substantially horizontal plane, and gage members situated at opposite sides of the path of oscillation of the tool, one of said gage members having its work-engaging portion farther than the other above the plane of presentation of the work.

3. In a machine of the class described, a movable fastening-pulling member, gage members situated at opposite sides of the path of the pulling member, and means arranged independently to vary the distance of the gage members from work presented to the tool.

4. In a tack-pulling machine, an oscillatory tack-pulling tool, a gage arm situated at one side of the tool, a contact member rotatable upon the arm for engagement with the work, and a gage member situated at the opposite side of the tool from the rotatable member.

5. In a tack-pulling machine, a frame, an

oscillatory tack-pulling tool, a gage arm situated at one side of the tool and mounted on the frame for adjustment into different positions heightwise of the tool and a gage member situated at the other side of the tool and mounted on the arm for adjustment relatively thereto.

6. In a tack-pulling machine, a frame, a tack-pulling tool mounted to oscillate thereon, a gage member variable in position upon the frame with respect to the tool, and a second gage member adjustably mounted upon that first mentioned.

7. In a tack-pulling machine, a frame, a tack-pulling tool mounted to oscillate thereon, a gage arm variable in position upon the frame, a gage roll rotatable upon the arm, and a gage member adjustably mounted upon the arm and extending upon the opposite side of the tool from the roll.

8. In a tack-pulling machine, a frame, an oscillatory tack-pulling tool, a gage member located adjacent to the tool and mounted upon the frame for movement into position to act as a guide for work presented to the tool, and a second gage member located adjacent to the tool and mounted on the frame for movement relatively to the tool and to the first-mentioned gage member into position to limit the extent to which the work may approach the tool.

9. In a tack-pulling machine, a frame, an oscillatory tack-pulling tool, and gage members located upon opposite sides of the path of movement of the tool and mounted upon the frame for adjustment relatively to each other and the tool into positions in which one of the gage members is farther removed than the other from the point of engagement of the tool with the work presented to the tool to act as a stop for determining the depth of engagement.

10. In a tack-pulling machine, a frame, an oscillatory tack-pulling tool mounted upon the frame, and gage members situated upon opposite sides of the tool and variable in position relatively to the tool and to each other.

11. In a tack-pulling machine, a frame, a tack-pulling tool mounted to oscillate thereupon, a gage member mounted upon the frame and variable in position with respect to the tool, and a second gage member mounted upon the frame and variable in position with respect to the tool and to the first-mentioned gage member independently thereof.

12. In a tack-pulling machine, a frame, a tack puller bar located within the frame, the frame having bearing surfaces against which one side of the bar is positioned, and removable bearing plates slidably mounted in the frame for engaging the opposite side of the bar.

65 13. In a tack-pulling machine, a frame, a

tack puller bar located within the frame, and bearing plates for engaging one side of the tack puller bar having laterally extending flanges for engaging portions of the frame rigidly to secure the plates in position.

70 14. In a tack-pulling machine, a frame, a tack puller bar located within the frame, a bearing plate for engaging one side of the tack puller bar and having a flange, and a guide member located on the frame for engaging the flange to secure the plate in position.

75 15. In a tack-pulling machine, an open-ended arm, a plate closing the greater portion of the open end of the arm, said plate having an opening, and an oscillating lever located within the arm and having a curved end portion extending through the opening in the plate.

80 16. In a tack-pulling machine, a hollow open-ended arm, a projection upon the arm closing a portion of the opening at the end thereof, an oscillatory lever located within the arm and having an end portion extending through the opening, and a tack-pulling tool 85 mounted upon the end of the lever outside of the arm, said end portion of the lever being curved on opposite sides of the projection to prevent tacks engaged by the tool from entering the arm.

90 In testimony whereof I have signed my name to this specification.

FRED L. MACKENZIE.
